METHOD OF CREATING A DESIGN
AND ARTICLE

Roy W. Lundquist, Chicago, Ill.

Application September 30, 1935, Serial No. 42,837

5 Claims. (Cl. 41—23)

My invention relates to a method of creating designs or patterns and to the finished creation itself in woods, compositions or the combination of different materials for use in furniture, wall 5 coverings or other articles or places in which my designs can be used.

Among the objects of my invention are the following: to create a method of creating a design so as to obtain an inlay effect in the materials 10 used without the necessity of separately inserting each individual segment of the design; to create a method of controlling the shape of the segments of the finished pattern after the primary stock has been cemented together and during such sub- 15 sequent addition of stock as may be added to appear in the finished design; to supply a method for creating a design in which cheaper materials may be used without the loss of design effect and to produce a method requiring less skill on the 20 part of the operator than is required in the art of parquetry, and such other objects, advantages and capabilities as will later more fully appear and which are inherently possessed by my invention.

Referring to the drawings, my figures are perspective views of the following: Fig. 1 is a primary sheet; Fig. 2 is a primary block; Fig. 3 is a sheet cut from the primary block on line 3—3 of Fig. 2; Fig. 4 is a design block made up 25 of sheets shown in Fig. 3; Fig. 5 is a sheet cut from the design block on line 5—5 of Fig. 4; Fig. 6 is a design block made up of sheets cut from Fig. 2 and primary sheets; Fig. 7 is a design sheet cut on line 7—7 of the block shown in 30 Fig. 6; Fig. 8 is an advanced design block; and Fig. 9 is a design block showing visible adhesive.

While I have shown in the accompanying drawings the preferred method and a preferred embodiment of my invention yet I wish it understood that the same are susceptible of modification and change without departing from the spirit of my 35 invention.

My invention more in detail comprises taking a primary sheet or strip 10 of wood, composition 40 or any desired material, and placing adhesive material on one surface thereof. I then take a second primary sheet or strip 11 of wood, composition or other desired material of the same or of a different color, grain, texture, or thickness 45 from the first sheet or strip 10 and lay said second sheet or strip 11 upon the adhesive covering a surface of said first sheet or strip 10. I may, of course, apply the adhesive to the second sheet or strip 11 before laying it against the 50 first sheet or strip 10, or adhesive may be applied 55

to both the contacting surfaces of sheets or strips 10 and 11. I then apply an adhesive to either of the exposed faces of the second primary sheet or strip 11 and in turn superimpose upon it primary sheet or strip 12 which may also be glued and which again may be of any desired material of the same or different color, texture or thickness with reference to either primary sheets or strips 10 or 11. I then continue the operation of applying adhesive to the exposed face of the last superimposed primary sheet or strip or to the next strip or both and affixing to it a contacting primary sheet or strip of the same or any of a different color, texture, grain, or thickness from the other primary sheets or strips and continue this operation until I have built up the primary block 13 shown in Fig. 2 of the drawings. This completes the first step in controlling the design which I desire to create. This primary block 13 itself may be used as a design block.

My next step in my method is to cut the primary block 13 either at right angles to the primary sheets or strips or obliquely across the primary sheets or strips into a plurality of secondary sheets or strips 14 of desired thickness 25 or thicknesses. If the primary block 13 is to be used as a design block then the secondary sheets or strips 14 cut therefrom are finished 30 design strips ready for use as shown for purposes of illustration in Fig. 3.

Another step in my method is to take one of the secondary sheets or strips 14, apply adhesive to one side of it and to superimpose upon it another secondary sheet or strip 14, either glued or not, so placed as to give the staggered arrangement shown in Fig. 4. A plurality of these secondary sheets or strips 14 superimposed upon each other will create the design block 15 as clearly shown in Fig. 4. Design sheets or strips 16 are then cut from design block 15 and are 35 then finished ready for use in furniture, such as desks, chairs or the like, or for use on walls, coverings or other places, as shown for purposes of illustration in Fig. 5.

A slight variation of my method is to take 45 secondary sheets or strips 14 from primary block 13 and to superimpose them between a plurality of primary sheets or strips 10 to create the design block 17 as shown in Fig. 6 of the drawings. Design strips 18 may be cut from block 17 as 50 shown in Fig. 7.

Another step which I may take in the creation of the design is to cut sheets or strips either at right angles or obliquely from design blocks such as 15 and 17 and to cement together these de- 55

sign sheets or strips 19 and 20 to form a further new advanced design block 21 as shown for purposes of illustration in Fig. 8. Design sheet 19 is cut from block 17 approximately on line 8-8 of Fig. 6 and design sheet 20 is cut from block 15 on approximately line 8-8 of Fig. 4. In this way by the cutting of design sheets or strips from my design blocks I may make my advanced subsequent design block as complicated in figure as may be desired. The next step would be to cut advanced design sheets from the advanced design block. It is also possible that with each of the design blocks I may also interpose and cement primary sheets between the design sheets 15 to achieve a different design effect on my advanced design block, from which are then cut advanced design sheets or strips.

I have also found it desirable to use an adhesive 22 that has color and thus accentuates 20 the design as clearly shown in design block 23 in Fig. 9. The adhesive may also have various widths and thus act not only as an adhesive but a material forming part of the design.

I find it desirable to use thin sheets or strips 25 of material so that interlocking joints will be unnecessary and the sheets will be held together by the adhesive.

In my invention I may also use thicker pieces or blocks of material and in some instances 30 combine thin and thick pieces of material.

Having thus described my invention, I claim:

1. The method of creating a design comprising taking a plurality of primary sheets and cementing them together to form a primary block, cutting 35 the primary block across the primary sheets to form secondary sheets, taking a plurality of said secondary sheets and cementing them together in staggered relation to form the first design block, taking a plurality of secondary sheets 40 and primary sheets and cementing alternately secondary sheets and primary sheets together to form a second design block, cutting design sheets from both the first and second design blocks and cementing a plurality of said design sheets together in desired relation to form a third design 45

block and cutting design sheets from said third design block.

2. The method of creating a design comprising building up a design block with a plurality of cemented together pieces to form one design, the 5 building up of a second design block with a plurality of cemented together pieces to form a different design, the cutting of design pieces from both of said design blocks, the cementing together of said design pieces to form an advanced 10 design block, and the cutting of advanced design pieces from said advanced design block.

3. The method of creating a design having segments giving an inlay appearance comprising 15 cementing together a plurality of sheets of desired color, grain, thickness, texture and substance to form a block, cutting said block across said sheets obliquely so as to obtain design sheets, cementing said design sheets together to form a second block, and cutting said second block 20 across said design sheets to obtain inlay appearing sheets.

4. The method of creating a design having segments giving an inlay appearance comprising 25 cementing together a plurality of sheets of desired color, grain, thickness, texture and substance to form a block, cutting said block across said sheets to obtain design sheets, cementing 30 said design sheets in staggered relation to form a second block, and cutting said second block across said design sheets to obtain inlay appearing sheets.

5. An article of the class described comprising 35 a plurality of primary sheets of material of desired color, grain, thickness, texture and substance, a plurality of secondary sheets of desired color, grain, thickness, texture and substance, groups of said primary sheets alternating 40 in position with groups of said secondary sheets, and a visible means of desired color and width between each of said sheets and groups for firmly uniting same together and to become part of and complete the design.

ROY W. LUNDQUIST. 45
